UNITED STATES PATENT OFFICE.

BENJAMIN OBORN, OF MARION, OHIO.

HAY-ELEVATOR.

SPECIFICATION forming part of Letters Patent No. 308,275, dated November 18, 1884.

Application filed September 20, 1884. (No model.)

To all whom it may concern:

Be it known that I, BENJAMIN OBORN, of Marion, in the county of Marion and State of Ohio, have invented certain new and useful 5 Improvements in Hay-Elevators; and I do hereby declare the following to be a full, clear, and exact description of the invention, such as will enable others skilled in the art to which it appertains to make and use the same.

10 My invention relates to an improvement in hay-elevators, the object of the same being to provide an elevator in which the elevator proper shall be swiveled or pivotally secured to the car in such a manner as to readily adjust itself to the line of draft, a further object being to provide simple, durable, and efficient means for locking the block in elevated adjustment and for automatically releasing it. With these ends in view my invention consists in certain features of construction and 20 combinations of parts, as will be hereinafter described, and pointed out in the claims.

In the accompanying drawings, Figure 1 is a view of the elevator and carriage in side elevation; Fig. 2, a transverse vertical section through the swivel-bolt; and Fig. 3 is a view in end elevation of a portion of the block G.

The carriage A is supported upon four wheels, 30 a and a', two wheels running on each rail of a single track, B. The bed of the carriage is provided with a vertical perforation or semi-cylindrical bearing, b, centrally located therein. The elevator proper, C, is secured to the bed of the carriage by a pivotal bolt, c, which fits in the perforation or bearing b, and is allowed a free rotary motion therein. The bearing b for the pivotal bolt is preferably formed by semi-cylindrical recesses b', formed in the 35 inner faces of the half-sections of the car, which sections, when bolted together, secure the pivotal bolt in position. The ends of the elevator are provided with hook projections d, which engage laterally-projecting flanges E on the ends of the carriage-bed when the elevator is in position for traveling in either direction. The lower central portion of the elevator C is provided with a hook, F, formed integral therewith or rigidly secured thereto, 40 the portion of the elevator located above the

point of the hook having an oblique direction upwardly over the bite of the hook.

G is the movable block, provided with a single sheave, g. The operating-rope H is secured at one end to the elevator at h, and leads 55 from thence under the sheave g, thence over the pulley I, journaled in C, and off to the operator. The block-strap i terminates upwardly in two branches connected by a cross-bar, k. The operating-rope is so secured to 60 the elevator that the block G will rise in a vertical line passing through the bight of the hook F; hence as the block rises the cross-bar k will engage the outer rounded portion of the hook F, and the block will be thereby tilted 65 out of line; but as soon as the bar k strikes the oblique surface f above the hook it will be positively thrown over into the bight of the hook by the combined effect of its own inclination and the oblique surface against which 70 it impinges. A pair of trip-levers, L, are pivotally secured to the elevator C—one on each side thereof—by a bolt or pair of studs, l. The outer ends of these levers are bent upwardly, as shown, and riveted or bolted together, thereby causing the levers to act as 75 one. The inner ends of the levers, when they rest in their normal positions, extend over the bights of the hooks slightly below the oblique surfaces f, while their outer ends lie in close 80 proximity to the under side of the track B, in a position to engage the stop m. The inner arms of the levers are provided with depending curved arms N, the ends of which are adapted to take under a longitudinal rib, n, 85 formed on the cross-bar k, when the latter is located in the bight of the hook.

The operation of the elevator is as follows: Suppose the carriage to be located over the load to be lifted, as shown in Fig. 1. The 90 carriage is now held against motion on the track by the outer ends of the lever L in contact with the stop m. As the block G reaches its elevated position the cross-bar k lifts the inner ends of the levers L, thereby releasing 95 the outer ends from the stop m, and at the same time drops into the bight of the hook F, locking the load in an elevated position as the carriage moves along the track. As the carriage returns to its position over the load the 100

outer ends of the levers L are depressed by the stop m, and the arms N take under the rib n of the cross-bar and release it from the hook F. My invention involves a radical departure in the construction and operation of hay elevators and carriers—viz., the elevator has a free rotary motion about the pivotal bolt, and will automatically adjust itself to the line of draft, so that the carriage is at any time reversed and run in the opposite direction by drawing the operating-rope in that direction, while the end bearings of the rotary section on the carriage-bed prevent undue strain on the pivotal bolt, and give it, when in position for travel, the strength of a non-reversible elevator. The small number of parts employed in the construction of the above-described elevator, their strength, and ready adjustment combine to make the elevator efficient, durable, and inexpensive.

It is evident that slight changes may be made in the form and arrangement of the several parts above described without departing from the spirit and scope of my invention; hence I do not wish to be understood as limiting myself strictly to the construction herein set forth; but,

Having fully described my invention, what I claim as new, and desire to secure by Letters Patent, is—

1. In a hay-elevator, the combination, with a track, a carriage, and a reversible elevator-section centrally pivoted to the lower face of

the carriage and provided with a rigid depending hook, of a lever pivoted to the reversible elevator-section for disengaging the block from the hook. 35

2. In a hay-elevator, the combination, with a carriage having a depending hook, of an elevator-block the frame of which is provided with a cross-bar and ribs n, and the lever adapted to engage the ribs and move the block from off the hook. 40

3. In a hay-elevator, the combination, with a carriage provided at opposite ends with outwardly-projecting flanges, of a reversible elevator-section provided with inwardly-projecting hooks, which latter overhang the flanges of the carriage, and a bolt pivotally connecting the reversible section to the carriage, substantially as set forth. 45 50

4. In a hay-elevator, the combination, with a track having a step or stop thereon, a carriage mounted on said track, and a reversible section pivoted to the carriage by a single bolt 55 and provided with a depending hook, of the elevator-block and the lever pivoted to the reversible section, all of the above parts constructed as described.

In testimony whereof I have signed this specification in the presence of two subscribing witnesses.

BENJAMIN OBORN.
